UNITED STATES PATENT OFFICE.

JAMES P. O'CONNELL, OF CROMPTON, RHODE ISLAND, ASSIGNOR OF ONE-THIRD TO EDGAR L. MERROW, OF MALDEN, MASSACHUSETTS, AND ONE-THIRD TO CHARLES D. ROBINSON, OF CROMPTON, RHODE ISLAND.

GUIDE-WIRE FOR SPINNING-MACHINES.

1,117,596.

Specification of Letters Patent. Patented Nov. 17, 1914.

Application filed October 22, 1913. Serial No. 796,616.

To all whom it may concern:

Be it known that I, JAMES P. O'CONNELL, a citizen of the United States, residing at Crompton, in the county of Kent and State 5 of Rhode Island, have invented a new and useful Improvement in Guide-Wires for Spinning-Machines, of which the following is a specification.

This invention relates to certain new and 10 useful improvements in guide wires for spinning machines, and the object of the invention is to provide an improved structure of guide in which the same is disposed substantially in alinement with the top of 15 the finger board, while the contractor is disposed in proximity to the top of the spindle so as to reduce the ballooning of the 20 yarn during spinning.

In the drawings—Figure 1 is a vertical 25 section of the invention. Fig. 2 is a front end elevation. Fig. 3 is a bottom plan view. Fig. 4 is a perspective view of the guide wire, and Fig. 5 is a similar view of a 30 modified form of guide wire.

The finger board 1 has the depending tail 2 of a plate 3 secured thereto, the tail 2 being hinged at 4 to the plate 3. The plate 3 has a depending portion 5 at its front end which portion 5 is apertured at 6 and slotted 35 at 7.

The guide wire is formed to have a horizontal substantially J-shaped part 8 the long leg of which is received in the aperture 6. The part 8 is firmly and adjustably secured 40 to the under face of the plate 3 by means of a nut and bolt 9. The long leg of part 8 is bent downwardly at 10 and is then further bent to provide a horizontal eye 11, which eye forms a contractor, the wire 45 being continued upwardly from the eye and inclined rearwardly at 12 and then further continued downwardly at an incline at 13 and formed with a kink catcher 14. The parts 13 and 14 form a U-shaped guide for 50 the thread T, which guide is located sub-

stantially in alinement with the top of the plate 3.

In Fig. 5 the guide structure is similar to that shown in the remaining figures, except that the kink catcher 14' is formed 50 by extending the leg 15 of the portion 16 downwardly, the leg 15 being received in the slot 7 of the plate 3, while the leg 13' of the guide 17 of the contractor 11' is shortened.

The thread passing from the rolls extends through the guide formed by the parts 12 and 13 in Fig. 1 and the part 16 in Fig. 5, and then passes through the contractor 11 or 11' in Fig. 5 and thence to the spindle 60 S, whereby it will be seen that the guide may be formed practically on a line with the top of the finger board, while the contractor may be disposed at a point in close 65 proximity to the top of the spindle, which greatly reduces the ballooning of the yarn during the spinning.

Having thus described my invention, I claim as new and desire to secure by Letters Patent;—

In a guide wire for spinning machines, a wire member having a part for securement to the finger board, one end of said part being extended downwardly and bent to form a closed contractor eye which extends slightly below the finger board and being further bent upwardly and then extended downwardly to form a U-shaped guide, the closed end of said guide being disposed in substantially the same horizontal plane with the finger board and adjacent to the eye to enable the thread to be placed through the eye and guide in one operation.

In testimony whereof I have signed my name to this specification in the presence 85 of two subscribing witnesses.

JAMES P. O'CONNELL.
